(57) **CLAIM**

The ornamental design for a motorcycle gauge trim, as shown and described.

DESCRIPTION

FIG. 1 is a top perspective view of the motorcycle gauge trim of the present invention.

FIG. 2 is a front elevation view thereof.

FIG. 3 is a rear elevation view thereof.

FIG. 4 is a top view thereof.

FIG. 5 is a bottom view thereof; and,

FIG. 6 is a left side view thereof, the right side being a mirror image thereof.

Those portions of the motorcycle gauge trim shown in broken lines, namely the rear side, the gauge openings, and front surface portions, form no part of the claimed design.
